US0D1089988S

(12) **United States Design Patent** (10) **Patent No.:** **US D1,089,988 S**
(45) **Date of Patent:** ** *Aug. 26, 2025

(54) **DUAL-SOLE SHOE WITH RED STRIPE AND OUTSOLE PATCH**

(71) Applicant: **Gavrieli Brands LLC**, Beverly Hills, CA (US)

(72) Inventors: **Kfir Gavrieli**, Beverly Hills, CA (US); **Dikla Gavrieli**, Beverly Hills, CA (US)

(73) Assignee: **Gavrieli Brands LLC**, Beverly Hills, CA (US)

(*) Notice: This patent is subject to a terminal disclaimer.

(**) Term: **15 Years**

(21) Appl. No.: **29/956,273**

(22) Filed: **Aug. 6, 2024**

Related U.S. Application Data

(63) Continuation of application No. 29/858,416, filed on Oct. 31, 2022, now Pat. No. Des. 1,043,063, which is a continuation of application No. 29/758,505, filed on Nov. 16, 2020, now Pat. No. Des. 968,057, which is a continuation of application No. 17/001,360, filed on Aug. 24, 2020, now Pat. No. 11,825,906, which is a continuation of application No. 15/905,239, filed on Feb. 26, 2018, now abandoned, which is a continuation of application No. 15/204,763, filed on Jul. 7, 2016, now Pat. No. 9,930,925, which is a continuation of application No. 14/266,599, filed on Apr. 30, 2014, now Pat. No. 9,398,786, which is a continuation of application No. 13/207,397, filed on Aug. 10, 2011, now Pat. No. 8,745,893.

CLAIM

The ornamental design for a dual-sole shoe with red stripe and outsole patch as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of our new design of a dual-sole shoe with red stripe and outsole patch, in which the outsole patch is hatched using the USPTO convention of solid vertical lines for red or pink (e.g., Pantone 169-Pantone 171, any one of Pantone 176-Pantone 277, any one of Pantone 483-Pantone 485, any one of Pantone 490-Pantone 510, any one of Pantone 670-Pantone 680, any one of Pantone 691-Pantone 711, Pantone 805 or Pantone 806, any one of Pantone 1765-Pantone 1955, any one of Pantone 2365-Pantone 2385, any one of Pantone 4985-Pantone 5035, or any one of RAL 3000-RAL 3033);

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;
FIG. 7 is a back view of the design of FIG. 1;
FIG. 8 is a perspective view of another embodiment of our new design of a dual-sole shoe with red stripe and outsole patch;

FIG. 9 is a first side view of the design of FIG. 8;

FIG. 10 is a second side view of the design of FIG. 8;

FIG. 11 is a top view of the design of FIG. 8;

FIG. 12 is a bottom view of the design of FIG. 8;

FIG. 13 is a front view of the design of FIG. 8;

FIG. 14 is a back view of the design of FIG. 8;

FIG. 15 is a perspective view of another embodiment of our new design of a dual-sole shoe with red stripe and outsole patch;

FIG. 16 is a first side view of the design of FIG. 15;

FIG. 17 is a second side view of the design of FIG. 15;

FIG. 18 is a top view of the design of FIG. 15;

FIG. 19 is a bottom view of the design of FIG. 15;

FIG. 20 is a front view of the design of FIG. 15;

FIG. 21 is a back view of the design of FIG. 15;

FIG. 22 is a perspective view of another embodiment of our new design of a dual-sole shoe with red stripe and outsole patch;

FIG. 23 is a first side view of the design of FIG. 22;

FIG. 24 is a second side view of the design of FIG. 22;

FIG. 25 is a top view of the design of FIG. 22;

FIG. 26 is a bottom view of the design of FIG. 22;

FIG. 27 is a front view of the design of FIG. 22;

FIG. 28 is a back view of the design of FIG. 22;

FIG. 29 is a perspective view of another embodiment of our new design of a dual-sole shoe with red stripe and outsole patch;

FIG. 30 is a first side view of the design of FIG. 29;

FIG. 31 is a second side view of the design of FIG. 29;

FIG. 32 is a top view of the design of FIG. 29;

FIG. 33 is a bottom view of the design of FIG. 29;

FIG. 34 is a front view of the design of FIG. 29;

FIG. 35 is a back view of the design of FIG. 29;

FIG. 36 is a perspective view of another embodiment of our new design of a dual-sole shoe with red stripe and outsole patch;

FIG. 37 is a first side view of the design of FIG. 36;

FIG. 38 is a second side view of the design of FIG. 36;

FIG. 39 is a top view of the design of FIG. 36;

FIG. 40 is a bottom view of the design of FIG. 36;

FIG. 41 is a front view of the design of FIG. 36; and,

FIG. 42 is a back view of the design of FIG. 36.

The long broken lines illustrating the half moon patch and the groove in the above described Figures are for illustrative purposes only and form no part of the claimed design. The short broken lines in the above described Figures depict stitching, which forms no part of the claimed design.
